UNITED STATES PATENT OFFICE.

CASIMIR DE PROSZYNSKI, OF LONDON, ENGLAND.

PROJECTION APPARATUS.

1,193,998.

Specification of Letters Patent.

Patented Aug. 8, 1916.

Application filed July 20, 1912. Serial No. 710,617.

To all whom it may concern:

Be it known that I, CASIMIR DE PROSZYNSKI, a subject of the Czar of Russia, residing at 7 Montague street, London, England, 5 have invented new and useful Improvements in Projection Apparatus, of which the following is a specification.

The object of the present invention is to produce a projection apparatus for cinematographs, copying lanterns and similar lanterns, in which an incandescent electric lamp may be advantageously used as the 10 source of light.

The chief difficulties in the way of employment of incandescent electric lamps for cinematographs are caused by the necessity of placing the light emitting body in close proximity to the picture and of providing for an easy adjustment of the lamp with regard to the picture and a quick removal of the lamp apparatus for the purpose of exchanging the lamp or the pictures.

According to the present invention the distance between the light emitting body or 25 filament and the picture is reduced to a minimum by pivotally mounting the lamp or preferably the whole lantern, that is the lamp and the lens combination or condenser directly upon the wall of the casing or stand 30 in or upon which the pictures are guided, and also by reducing to a minimum the distance between the light emitting body and the portion of the bulb interposed between that body and the lens or condenser. As 35 with electric incandescent lamps of ordinary construction the reduction of the distance between the filament and the wall of the bulb would cause a rapid deterioration of the lamp due to the distribution of the 40 deposit over a comparatively small area, the present invention provides means for counteracting the effect of the reduction of the distance aforesaid, whether the reduction be obtained by a reduction of the size or 45 diameter of the bulb without any alteration of the normal arrangement of the filament, or by an eccentric mounting of the light emitting body or filament with regard to the axis of the bulb, or by a combination of 50 the two devices referred to. Generally speaking, the broad feature of this part of my invention consists in so constructing the lamp as to concentrate the formation of the

deposit due to the burning of the lamp upon a comparatively small portion of the surface 55 through which the light rays first pass before reaching the lens or picture, and in simultaneously providing means for moving the said surface with regard to the light emitting body so as to enable fresh portions 60 of the same to be brought into operation as soon as the used portion has deteriorated owing to the deposit formed thereon.

In the accompanying drawings Figure 1 is a sectional plan illustrating one arrangement of the improved lamp applied to a projection apparatus for cinematographs. Fig. 2 is a detail elevation of the locking plate by which the lamp is secured. Fig. 3 is a section through the lamp and its casing 70 only, the plane of the section being perpendicular to the plane of the section Fig. 1 and showing parts seen in Fig. 1 when looking from left to right. Fig. 4 is a transverse sectional elevation of the lamp casing 75 and lens frame shown in Fig. 1. Fig. 5 is a diagrammatic illustration of a second construction of the lamp. Fig. 6 is a view similar to Fig. 1 of a modified arrangement and Fig. 7 is a detail view of the intermediate 80 ring shown in Fig. 6.

In Fig. 1, 1 represents the picture to be illuminated which is held in the frame 1^a of the projection apparatus. To this frame is hinged at 2 the lens frame 3 having a central aperture surrounded by a flange 30 in which is fixed the lens combination or the condenser 4. The lens frame 3 may be swung upon the pivot 2 for the purpose of changing the pictures and may be also easily detached from the frame 1^a by removing the pivot pin 2. Upon an outer flange 31 of the lens frame 3 is mounted a casing 5 containing the lamp, the said casing preferably fitting over the flange 31. The casing is 90 preferably made of sheet metal and may be adjusted upon the flange 31 for the purpose of regulating the distance between the lamp and the condenser. As a rule frictional contact due to the fit between the open 95 end of the casing 5 and the flange 31 of the lens frame may be sufficient for effecting the connection between these two parts but if desired other means of connection may be used.

The casing 5 is provided at its preferably

domed end with a socket 6 provided with an external screw thread and closed by means of a screw cap 32. Within the chamber inclosed by the socket 6 the screw cap 32 and the dome portion 33 is a ball or knob 7 which is clamped by means of the screw cap 32 against the lower portion of the casing 5. To the inner end of this knob 7 is secured an arm 7^a which serves to hold or support the lamp and is fitted with an insulating piece 7^b on which are mounted the locking plate 8 and the binding screw 9. The arm 7^a carries a lamp holding or supporting ring 10 which is in constant electrical contact with the other binding screw 11 through the holder 7^a, the ball shaped member 7, the screw cap 32 and the casing 5. The locking plate 8 is made of a springy material, and is provided with an opening 12 through which the rotatable button or stud 13 of the lamp is inserted. After the lamp has been inserted into the holder with the turn-button 13 through the opening 12, the button is turned through 90 degrees whereby the lamp is securely locked in the holder.

The lamp comprises in the construction shown a closed vacuum bulb 14 provided on the outside with a cylindrical metal sleeve 15 representing one terminal of the lamp and in contact with the ring 10 electrically connected with the terminal screw 11; the other electrode is represented by the button 13, which latter is in electrical contact with the blade 8 which connects it with the opposite terminal screw 9. It will be seen that the whole lamp may be easily inserted into, or removed from the casing 5 after removing the casing from the lens frame 3. The holder composed of the parts 7^a and 10 remains permanently in the casing, and being supported by the ball shaped member 7 enables the lamp to be adjusted in the casing 5 within certain limits in any desired direction, the cap 32 being tightened to secure the lamp in an adjusted position.

The lamp proper comprises in the construction shown in Figs. 1 and 3 a filament 16 placed in close proximity to the glass wall of the bulb 14. This arrangement of the filament with regard to the wall of the bulb brings the illuminating point into close proximity to the picture to be illuminated, whereby the efficiency of the lamp is considerably increased, more especially as the lamp is mostly used in connection with very small pictures. As owing to the close proximity of the filament to the transparent surface through which the rays pass, a comparatively rapid blackening of that surface must occur, a relative movement is provided for between the filament 16 and the glass or transparent medium through which the light first passes, which in this modification

is the bulb 14 only, in such a manner that 65 fresh parts of the surface may be brought into operation as the translucency at the point nearest the filament deteriorates owing to the deposition on the glass of carbon or other matter resulting from the burning of the lamp. The bulb 14 inclosing the filament 16 may be readily turned by hand about its axis from outside the casing 5 by means of the portion 15 protruding through an aperture in the casing 5. It may be mentioned that the turn button 13 is rotatably mounted on its stem in order to retain the locking engagement of the button with the spring plate 8 during the adjustment of the bulb. 80

The filament itself does not take part in the movement of the bulb, being mounted in such a manner as to retain its position during the rotation of the bulb. As may be seen from Figs. 1 and 2, the filament is 85 mounted upon a revoluble or pivotal support provided with a counter-weight 17 and loosely arranged upon the horizontal pin or rod 18 made of glass or similar material. The rod 18 preferably consists of a glass 90 tube embedded in the plug 34 of the bulb. Upon the glass tube 18 are mounted two metal rings 19 which serve for electrically connecting the filament 16 with the supply wires. One of these supply wires namely 95 that marked 35 is passed through the tube 18 and is connected at one end to the right hand ring 19 and at the other end to a part integral with the stem of the turn button 13. The other ring 19 is connected by a 100 wire 36 outside of the tube 18 with the metal sleeve 15. Upon the metal rings 19, 19 are mounted two bent wires or rods 37 supporting the filament 16. These wires or rods 37 are connected by a cross member 20, 105 preferably made of glass, which may be formed in one with the counter-weight 17 which may take the form of a glass ball as shown. The transverse member 20 supports moreover a fork or U-shaped wire 21 carrying at the outer end of its prongs two end disks 22 made of metal or glass and serving as screens for preventing lateral radiation. The object of these screens is to prevent the blackening or soiling of the adjacent bulb 110 surface by lateral radiation. A similar purpose is served by the transverse member 20 which not only stiffens the support, but acts as screen in the radial direction and may also act as a reflector. 115

The filament 16 may be of any suitable kind, but proper regard must be had to the particular requirements and object of the lamp, and the filament should preferably be so shaped and arranged as to obtain a maximum incandescent surface within a minimum space. 120

In order to avoid accidental contact be-

tween the coils or sections of the filament, intermediate supports made of thin wire may be used as in ordinary incandescent lamps. In addition, projections or supports 5 made of the usual material, such as chalk might be used, but in most cases no additional supports are required.

The rings 19 may be provided with tongues 23, 24 which serve as lateral stops 10 for the arms or supports 37 rotatably mounted upon the rings. The tongues are bent out of the way when mounting the arms 37 and after the latter have been placed upon the rings 19 the tongues 23, 24 are bent outwardly.

Another way of avoiding the rapid deterioration of the lamp which would otherwise be caused by the proximity of the filament to the bulb, consists in mounting the 20 filament in close proximity and in fixed relation with the bulb and providing a transparent screen between the filament and the bulb which screen is so arranged as to move relatively to the filament and the bulb when 25 the position of the lamp is altered. In this construction therefore the position of the filament with regard to the bulb is not altered, but owing to the relative movement 30 of the screen fresh surfaces of the screen are successively brought into operation. As 35 in this case it is the screen on which the deposit takes place the same object is attained as with the previous construction. An arrangement of this kind is shown in 40 Fig. 5 in which the filament 16 is placed in close proximity to the end or dome portion of the bulb. Upon the filament support 38 is fixed an inclined pivot or pin 40 upon which is loosely mounted the revolute 45 screen 41. This screen may have the shape of a hollow hemisphere made of glass and provided with a weight 42 which is eccentrically arranged and has therefore the tendency to move always into a certain position with regard to the shaft 40. When 50 the lamp is turned about its axis the pivot 40 is carried around, and the cap or screen 41 is moved upon the shaft by the counter-weight 42 so that a fresh portion of the screen is brought opposite the filament 16. Although 55 this arrangement may be simpler in some respects than that shown in Figs. 1 to 4, in practice the latter construction may be found to work with better practical results than may be obtained with the lamp shown in Fig. 5.

Figs. 6 and 7 show a simplified arrangement of combined lamp and casing adjustable in relation to the lens. Similar parts 60 have reference numerals similar to those used in describing Figs. 1 to 4. In Figs. 6 and 7 the flange part 31 is not integral with the lens frame 1^a but is adjustable thereon within limits by reason of the fixing screws

43 passing through slots 44. The lamp is 65 supported by means of its plug portion fitting in the aperture in the casing 5, the ring 15 making contact directly with the casing upon which the binding screw 11 is fixed as before. The parts 7^b, 8, 9 and 13 70 are as described with reference to Fig. 1. It will be understood that the filament can be positioned before the lens 4 with the greatest nicety owing to the fact that the flange part 31 can be adjusted owing to the 75 slots 44 and that the casing can be turned on the flange 31.

It will be seen from the foregoing that the invention aims at placing the light-giving body as near as possible to the picture 80 to be illuminated, this object being attained by the novel arrangement of the lamp or lantern directly upon the portion of the casing in which the picture is guided, and by the improved construction of the lamp 85 in which the distance between the light emitting body or filament and the transparent wall inclosing the same is reduced to a minimum without any disadvantage; owing to the provision of means for distributing the 90 deposit successively over a comparatively large area.

The invention is not restricted to the constructions shown in which the filament is placed eccentrically within the bulb. If desired the filament may be placed in the usual manner in or near the center of the bulb, and a very small bulb may be used in order to reduce the distance which the rays have to pass before they reach the lens or the picture. In order to avoid the rapid deterioration of the transparency of the bulb material, a screen of glass or other suitable material may be used which partly incloses the filament in the manner shown in Figs. 1 105 and 3 and causes the deposit to accumulate on a comparatively small portion of the inner wall of the bulb. The screen may be loosely mounted and counter-weighted so as to retain its position when the bulb is 110 turned in order to bring a fresh and clean portion of the same between the filament and the picture.

I claim:

1. An incandescent electric lamp for optical projection apparatus having a filament closer to one portion of the bulb than any other portion thereof, mechanical means for shifting the filament relative to the bulb and thereby causing the accumulation of deposit 120 from the filament to take place successively on different places of said bulb while maintaining the filament body incandescent; substantially as described.

2. An incandescent electric lamp having 125 a transparent wall and a filament closer to one portion of the wall than another portion thereof, mechanical means for shifting

one element relative to the other and thereby causing the accumulation of deposit from the filament to take place successively on different places on said wall without changing the position of the filament, substantially as described.

3. An incandescent electric lamp for optical projection apparatus having a filament and a transparent body in which the deposit from the filament has a tendency to accumulate on a restricted portion of the transparent body through which the light first passes, said filament being closer to one portion of the transparent body than another portion thereof, mechanical means for shifting one element relative to the other and thereby causing the accumulation to take place successively on different places of said body while maintaining the filament stationary, substantially as described.

4. An incandescent electric lamp for optical projection apparatus having a filament and a transparent body in which the deposit from the filament has the tendency to accumulate on a restricted portion of the transparent body through which the light first passes, said filament being closer to one portion of the transparent body than another portion thereof, mechanical means for shifting one element relative to the other and thereby causing the accumulation to take place successively on different places of said body while maintaining the filament in the same position and incandescent, substantially as described.

5. An optical projection apparatus for cinematographs, having an incandescent electric lamp for illuminating the picture, said lamp having a filament and a transparent body in which the deposit from the filament has the tendency to accumulate on a restricted portion of the transparent body through which the light first passes before reaching the picture, said filament being closer to one portion of the transparent body than another portion thereof, means for moving the said transparent body relative to the filament so as to bring fresh portions of the same between the filament and the picture, substantially as described.

6. Incandescent electric lamp for optical projection apparatus, comprising in combination a transparent wall, an incandescent body mounted nearer to one point of said wall than any other point, and means for shifting one element relative to the other to prevent concentration of the deposit by said body on one portion of said wall, substantially as described.

60 7. Incandescent electric lamp for optical projection comprising in combination an incandescent body arranged close to one point of its inclosing bulb, and mechanical means for shifting one element relative to the other

adapted to prevent concentrated deposits on one portion of said bulb from said incandescent body, substantially as described.

8. Incandescent electric lamp for optical projection comprising in combination an incandescent body arranged closer to one portion of its inclosing bulb than another portion thereof, and weighted pivotal means adapted to operate upon adjustment of said lamp to prevent concentration of deposits on one portion of said bulb from said incandescent body, substantially as described.

9. Incandescent electric lamp for optical projection comprising a pivotal support, an incandescent body, pivotally mounted on said support in closer proximity to one portion of the lamp bulb than another portion thereof, and a weight connected to said body, substantially as described.

10. An incandescent electric lamp for optical projection, having a pivot, a frame mounted on said pivot, an incandescent body on said frame closer to one portion of the lamp bulb than another portion thereof, screens secured on said frame laterally of said body for preventing blackening of the bulb by a lateral radiation of the deposit from the incandescent body, and a counterweight on said frame, and means for shifting the bulb to successively bring new portions thereof adjacent to the incandescent body, substantially as described.

11. A rotatable incandescent lamp for optical projection, comprising a weighted pivoted device, an incandescent body mounted on the pivoted device and supported in closer proximity to one portion of the lamp bulb than another portion thereof, said weighted pivoted device being adapted to maintain the incandescent body in a substantially stationary position when the lamp is rotated, substantially as described.

12. An incandescent electric lamp for optical projection comprising in combination an incandescent body arranged closer to one portion of its inclosing bulb than another portion thereof, a pivoted device having a counterweight for supporting the incandescent body and adapted to operate upon adjustment of said lamp to prevent concentration of deposits by said incandescent body on one portion of said bulb, and a holder adapted to rotatably support said lamp, substantially as described.

13. An incandescent electric lamp for optical projection comprising in combination an incandescent body arranged closer to one point of its inclosing bulb than another portion thereof, a weighted pivoted device for supporting said body and adapted to operate upon adjustment of said lamp to prevent concentration of deposit by said incandescent body on one portion of said bulb, a holder adapted to rotatably support said

lamp, and a ball-and-socket support for said holder, substantially as described.

14. An incandescent electric lamp for optical projection comprising an incandescent body arranged closer to one portion of its inclosing bulb than another portion thereof, a weighted pivoted device for supporting said body and adapted to operate upon adjustment of said lamp to prevent concentration of deposit by said incandescent body on one portion of said bulb, a holder adapted to rotatably support said lamp, a casing inclosing said holder and the bulb of said lamp, said casing having an opening through which the plug of the lamp extends, and a ball and socket connection on said casing for said holder, substantially as set forth.

15. An optical projection apparatus comprising a lens frame, a lens mounted therein, a lamp inclosing casing, a support on said frame for said casing, a lamp holder on said casing, and a lamp revolvably-mounted in said holder, said lamp comprising an incandescent body arranged nearer to the lamp bulb at a point opposite the lens than at any other point, substantially as set forth.

16. An optical projection apparatus comprising a lens frame, a lens supported therewithin, a lamp inclosing casing adjustably supported on said frame, a lamp holding device on said casing, and a lamp rotatably mounted in said device having its filament closer to the bulb at the point nearest to the lens than another point thereof, substantially as set forth.

17. An optical projection apparatus comprising a lens frame, a lamp inclosing casing, means on said frame adapted to support said casing, a lamp rotatably mounted in said casing, a flexible member mounted on said casing, revoluble means on the plug of said lamp adapted to engage said flexible member to secure said lamp, and means in said lamp for supporting the filament thereof closer to the lamp bulb at a point nearest to the lens frame than at any other point thereof, substantially as set forth.

18. An optical projection apparatus, comprising a lens frame, a cylindrical lamp inclosing casing having an open end, means on said frame for adjustably supporting the open end of the casing, a lamp having a filament supported in said casing, said filament being closer to one portion of the lamp bulb than to the other portions thereof, means for rotating the bulb with relation to the filament to successively present new portions thereof adjacent to the filament, and securing means on said casing to maintain the lamp in position; substantially as described.

19. An optical projection apparatus, com-

prising a picture support, a lens frame pivoted to said support, a cylindrical lamp inclosing casing, an annular projection on said frame adjustably engaging the open end of said frame, a lamp rotatably mounted in said casing and having a filament closer to one portion of the lamp bulb than to other portions thereof, and means for rotating the lamp bulb with relation to the filament to successively bring new portions of the bulb adjacent to the filament, and lamp securing means on said casing; substantially as described.

20. An incandescent lamp for optical projection, comprising an incandescent body arranged within a closed bulb, said incandescent body being closer to one portion of the bulb than any other portion thereof, means for rotating the bulb with relation to the incandescent body to successively bring fresh portions thereof adjacent to the incandescent body, and screens at the sides of said body and within said bulb for preventing lateral radiation; substantially as described.

21. An incandescent electric lamp for optical projection, comprising an incandescent body arranged closer to one point of its encircling bulb than any other portion thereof, said bulb being arranged to be rotated with relation to the incandescent body to successively bring fresh portions of the bulb adjacent to the incandescent body, screens at the sides of said body and within said bulb for preventing lateral radiation, and a screen behind said body and within the bulb for preventing backward radiation; substantially as described.

22. An incandescent electric lamp for optical projection comprising a bulb, a central stem in said bulb, a filament support pivotally mounted on said stem, a filament connected thereto, said filament being closer to one portion of the bulb than any other portions thereof, a counter-weight on said support, and screens on said support arranged partially around the filament, substantially as described.

23. An incandescent electric lamp for optical projection comprising a bulb, a central stem in said bulb, two rings loosely mounted on said stem, a rod projecting from each ring, a filament supported between said rods, said filament being closer to one portion of the bulb than any other portions thereof, a cross-member below said filament connecting said rods, and a counter-weight connected to said cross member, substantially as described.

24. An incandescent electric lamp for optical projection comprising a bulb, a central stem in said bulb, two rings loosely mounted on said stem, a rod projecting from each ring, a filament supported between said rods, said filament being closer to one portion of

the bulb than any other portions thereof, a counter-weight connected to said cross-member, a U-shaped wire extending from said cross-member to the sides of said filaments and disks on the ends of said wires to prevent lateral radiation, substantially as described.

In testimony whereof I have signed my name to this specification in the presence of two subscribing witnesses.
